UNITED STATES PATENT OFFICE.

JOHN P. GILSON AND MICHAEL GILSON, OF FREDONIA, WISCONSIN.

CONCRETE-MIXER.

1,237,028.

REISSUED

Patented Aug. 14, 1917.

Specification of Letters Patent.

Application filed February 5, 1917. Serial No. 146,682.

To all whom it may concern:

Be it known that we, JOHN P. GILSON and MICHAEL GILSON, both citizens of the United States, and residents of Fredonia, 5 in the county of Ozaukee and State of Wisconsin, have invented certain new and useful Improvements in Concrete-Mixers; and we do hereby declare that the following is a full, clear, and exact description thereof.

10 Our invention relates to new and useful improvements in concrete mixers, more particularly of that simpler type embodying a drum rotatably mounted in a yoke having a horizontal pivotal axis, whereby the drum 15 may be dumped by swinging the yoke on its axis.

It is in general the object of our invention to simplify and strengthen the structure and to improve the efficiency of concrete mixers 20 of this general nature, and it is more particularly an object to distribute the load strain of the mixing drum when in its operative mixing position, so as to relieve the bearing connection of the yoke and drum.

25 With the above and other objects and advantages in view, the invention resides more particularly in the novel combination, formation and arrangement of parts hereinafter described and pointed out in the appended 30 claims.

In the drawings:

Figure 1 is a vertical sectional view taken through a mixer constructed in accordance with our invention.

35 Fig. 2 is a horizontal sectional view through the supporting frame of the drum on the line 2—2 of Fig. 1.

40 Fig. 3 is a detail view showing the adjustable means for holding the drum in meshing engagement with its driving gear.

Referring now more particularly to the accompanying drawings, the supporting frame for the drum comprises end skeleton standards 5 connected at their lower ends by 45 a pair of skid beams 6 and by a beam 7 disposed adjacent their lower ends. The upper ends of the standards forming journals 7' receiving pintles 8 at the ends of the arms of a relatively wide drum supporting yoke 9, 50 the pintles 8 being preferably in the form of sleeves integral with the yoke arms.

55 The mixing drum comprises a pan-shaped bottom casting 10 and an annular mouth casting 11 having its outer portion taperingly reduced to facilitate discharge, and these

castings are connected by a cylindrical wall plate 12 bolted thereto. For journally mounting the drum in the yoke 9, the bottom casting thereof is provided with an outwardly projecting boss 13 engageable in a 60 socket portion of an outwardly projected boss 14 on the bight of the yoke, and both bosses are bored for the reception of a pivot bolt 15 fixedly secured in the drum boss 13. Thus a bearing for the bottom end of the 65 drum is afforded by the shaft 15, and also by the disposition of the boss 13 in the socket portion 14. An end thrust bearing for the drum is formed by ball bearings 16 between the bosses. 70

For rotating the drum, and for also affording a support for the mouth end thereof to relieve strain from the bearing of the inner end of the drum, the mouth casting of the drum is provided with an annular series 75 of gear teeth 17 and these gear teeth mesh with the teeth of a gear wheel 18 carried on a shaft 19 journaled in bearings 20 on a beam 21 which is carried by forwardly extending brackets 22 at the intermediate portion of the end standards 5. This gear wheel 18 is driven by a shaft 23 journaled in bearings 24 on the said beam 21 and carrying a beveled gear 25 meshing with bevel teeth on the side of the gear wheel 18. Fixed on the 80 outer end of the shaft 23 is a wheel 26 having a laterally projected crank handle 27.

Suitable mixing blades 28 are provided on the inner peripheral face of the drum, and it is noted that the drum may swing through 90 an arc of substantially 180 degrees from its meshing engagement with the gear wheel 18, to a position projecting downwardly at the opposite side of the supported frame, whereby to discharge the contents of the 95 mixer. For effecting this vertical swinging movement of the drum, an operating handle 29 is secured by the bolt 30 to one of the pintles 8. To provide a means whereby the drum is positively held in proper meshing 100 engagement of its teeth 17 with the gear wheel 18, the handle is extended past the bolt to form an abutting face 31 and intermediate pivoted to the adjacent standard 5 is a pawl 32 having a bolt 33 threaded in 105 one end and adapted to abut the face 31 of the lever, inward slipping movement being prevented by a lug 34 on the lever. The bolt 33 provides an adjustment whereby an exact meshing relation of the gear teeth may 110

- be insured, and the pawl upon being swung readily releases the drum for movement to its dumping position.
- For rotating the drum in its dumped position, the shaft 19 is extended thereunder in a downwardly inclined direction and carries at its lower end a gear wheel 35 adapted to mesh with the teeth 17 in the dumping position of the drum.
- From the foregoing description it is seen that an exceedingly simple, compact and readily operated concrete mixer has been provided, wherein the strains incidental to operation are distributed in such manner as to procure a maximum strength of the structure, particularly in view of the distribution of the load of the drum at both ends thereof, by the support afforded by the gear 18.
- What is claimed is:
1. A concrete mixer comprising a rotary, vertically tiltable drum, one end of said drum being open, a support for said drum, means for rotating the drum in one direction when its open end is disposed upwardly, means for rotating the drum in a reverse direction when said open end is disposed downwardly, including a continuously rotatable shaft disposed substantially parallel to the axis of the drum, a pair of gear wheels on the shaft, peripheral gear teeth on the drum adapted to be selectively meshed with the gear teeth, and means for rotating said shaft.
  2. A concrete mixer comprising a horizontally rotatable drum support, a mixing drum having one end rotatably secured to the support, an inclined shaft journaled under the drum, a pair of gear wheels on the shaft, peripheral gear teeth on the mixing drum, adapted to selectively mesh with the gear wheels, and means for rotating said shaft.
3. A concrete mixer comprising a support, a mixing drum rotatably secured therein, a shaft journaled under the drum substantially parallel to the axis thereof, and means carried by each end of the shaft for rotating the drum in one direction when in normal position and in reverse direction when in dumping position.
4. A concrete mixer comprising, in combination, a pair of supporting standards, a mixing drum rotatably and vertically mounted between said standards, peripheral gear teeth on the drum, a forwardly extending bracket formed on each standard, a transverse beam carried by said brackets, transversely extending and alined arms formed on said beam, bearings in said arms, a shaft journaled in said bearings and extending substantially parallel to the axis of the drum, gear wheels mounted on the shaft and adapted to be selectively engaged by the peripheral teeth of the drum for revolving said drum in one direction when in normal position and in a reverse direction when in discharging position, a beveled gear fixed to said shaft and juxtaposed the forward gear wheel thereon, laterally extending and transversely alined arms formed on said beam to one side of said other arms, a driven shaft journaled therein, and a beveled pinion gear on the inner end of the last named shaft and in mesh with the beveled gear of the first shaft substantially as described.

In testimony that we claim the foregoing we have hereunto set our hands at Fredonia, in the county of Ozaukee and State of Wisconsin, in the presence of two witnesses.

JOHN P. GILSON.
MICHAEL GILSON.
